UNITED STATES PATENT OFFICE.

CARL S. NORDEN, OF LYNN, MASSACHUSETTS, ASSIGNOR TO UNITED SHOE MACHINERY COMPANY, OF PATERSON, NEW JERSEY, A CORPORATION OF NEW JERSEY.

JOINT-MACHINE AND WELT-CUTTER.

1,023,953.

Specification of Letters Patent.

Patented Apr. 23, 1912.

Application filed December 14, 1907. Serial No. 406,424.

To all whom it may concern:

Be it known that I, CARL S. NORDEN, a citizen of the United States, residing at Lynn, county of Essex, Commonwealth of Massachusetts, have invented certain new and useful Improvements in Joint-Machines and Welt-Cutters, of which the following is a specification.

In the finishing of the shank of a welt shoe, after it has been lasted and before the welt has been cut or the shoe jointed, much difficulty has been experienced in securing the required smoothness of the upper at the shank and the desired neatness of the joint. This is due to the fact that in the welting operation the running on and off of the stitching which occurs at the point of joint between the heel seat and shank tends to throw out the rib of the inner sole and leave the inner seam in a position which so far overlies the margin of the inner sole that when the outer sole is stitched to the welt the table will strike the inner seam and thus guide the stitch away from its true line along the shank. When the shoe is trimmed therefore there is a liability that the trimmer will run into the stitching which will expose the same and ruin the shoe. In order to overcome this difficulty and secure the desired result without the delay caused by the slowness of hand work and clumsiness of the result, I have devised my present invention which automatically engages with the welt and upper at the required point and draws them smoothly over the last, presses back the inner seam to its normal position, and securely holds them while the operative fastens them in place.

This invention I have more fully disclosed in the accompanying specification in which I have described a machine which embodies my invention and in addition to this description I have set forth in the drawings forming a part of the specification views of such an embodiment to illustrate the principle of my invention.

Throughout the specification and drawings like reference numerals indicate corresponding parts and in the drawings Figure 1 is a side view of my machine, Fig. 2, an end view partly in section, Fig. 3, a plan view, Fig. 4, a perspective view showing a shoe positioned and under operation, Fig. 5,

a section of the welted and lasted upper at the shank, and Figs. 6 and 7 views of the cutting knife.

1 is a bed in which is formed a longitudinal slideway 2. 3 is a slide movable along said slideway and bearing a support 4 which through the coiled spring 5 affords a yielding support for a last 6 on a block 7 which is hinged on said slide 3. 8 is an adjustable toe support also mounted on the slide 3.

9 is a pair of oppositely disposed boxes in which are formed transverse slideways.

11 is a pair of oppositely disposed transverse slides which are normally retracted by the springs 10¹ in the slideways 10 and are simultaneously operated therein by means of bell-crank levers 12 pivoted in the boxes at 13 and having engagement at their upper ends with the slides 11 and at their lower ends connected by suitable rods to a treadle or other operating means (not shown). On the slides 11 are adjustably mounted pressure fingers 14 formed with crooked ends 14¹ which are adapted to slide over a last to draw the upper smoothly over it. The ends of these bent portions 14¹ are brought to a thin slightly rounded edge 14² which is adapted to catch the upper 20 and welt 21 at the seam 22, draw them smoothly over the last and at the same time press back the rib 23 to its normal position.

15 is a stop on the upper face of each finger 14 near its edge 14² on the side opposite to the shoe. As the welt end runs over this stop the operative may cut against it with a skiving cut allowing the welt to be severed uniformly on the two sides of the shoe.

16 is a stop adjustable at 16¹ to afford the proper location of shoes of different sizes and thus permit the operative to cut quickly and accurately at just the point desired.

The operation of the device is as follows. With the parts positioned as shown in Figs. 1-3, inclusive, a lasted and welted upper is placed with its last 6 on the spindle of the support 4 and bearing on the spring 5 with the toe resting on the support 8 which together with the heel stop 16 has been adjusted to suit the size of the work. The operative then draws the slide with the shoe heel first, toward him at the same time 100 pressing down on the shoe and rocking it

slightly forward. When the heel strikes the stop 16 the slides 10 are thrown forward by the levers 12 which are operated by any suitable means such as by foot treadle or by a power shaft. As the slides 10 advances the fingers 14 engage the seam 22 of the upper 20 and the welt 21 at the shank and cooperating with the upward pressure of the springs 5 and 7 draw the upper smoothly over the last pressing back the rib 23 which has been bent out by the welting machine and hold these parts until retaining tacks can be driven. With the parts thus held the operative may then cut the welt ends off evenly and accurately against the stops 15 by means of a cutting knife 17 shown in connection with Fig. 5. When the upper is finished the slides 10 are allowed to be returned by the springs and the slide 3 returned to its initial position in which the shoe may be removed and another piece of work substituted.

Various modifications may obviously be made in the form and arrangement of the parts of the embodiment of my invention shown without departing from its spirit.

What I therefore claim and desire to secure by Letters Patent is:

1. In a device of the class described, a slide way, a slide, a shoe support on said slide, a pair of oppositely disposed transversely acting slides near one end of said slide way, a finger on each slide having a thin edge which is adapted to bear between the welt and upper at the shank, and means to operate said transversely acting slides to cause the fingers to tighten the upper at the shank relatively to the upper in front and back of the shank.

2. In a device of the class described, a slide way, a slide, a shoe support on said slide, a pair of oppositely disposed transversely acting slides near one end of said slide way, a finger on each slide adapted to bear between the welt and upper at the shank, a cutting stop on each of said fingers, and means to operate said transversely acting slides.

3. In a device of the class described, a slide way, a slide, a shoe support hinged on said slide, a pair of oppositely disposed transversely acting slides near one end of said slide way, a finger on each slide adapted to bear between the welt and upper at the shank, a cutting stop on each of said fingers, and means to simultaneously operate said transversely acting slides to tighten the upper at the same time at opposite sides of the shoe and hold it while the upper is fastened and the welt cut against said stops.

4. In a device of the class described, a slide way, a slide, a yielding shoe support on said slide, a pair of oppositely disposed transversely acting slides near one end of

said slide way, a finger on each slide adapted to bear between the welt and upper at the shank and tighten the upper at the shank with relation to the upper in front and back of the shank, and means to simultaneously operate said transversely acting slides, said yielding shoe support pressing the shank snugly upwardly against said fingers.

5. In a device of the class described, a slide way, a slide, a yielding shoe support hinged on said slide, a pair of oppositely disposed transversely acting slides near one end of said slide way, a finger on each slide adapted to bear between the welt and upper at the shank, a cutting stop on each of said fingers, and means to simultaneously operate said transversely acting slides to tighten the upper at the same time at opposite sides of the shoe.

6. In a device of the class described means for supporting a lasted upper, and means on each side of the shoe including a thin edged finger shaped to enter the crease between the welt and upper of a welted shoe for engaging the upper at the shank to draw the same tight with relation to the upper in front and back of the shank.

7. In a device of the class described means for supporting a lasted upper, and oppositely acting thin blades on each side for engaging the upper at the shank simultaneously to draw the same tight with relation to the upper in front and back of the shank.

8. In a device of the class described means for supporting a welted and lasted upper, and means on each side shaped and arranged to engage the stitches of the seam which connects the welt and upper at the shank to draw the same tight with relation to the upper in front and back of the shank.

9. In a device of the class described means for yieldingly supporting a welted and lasted upper, and jaws on each side for simultaneously engaging the upper at the shank to draw the same tight with relation to the upper in front and back of the shank while the last is pressed upwardly against said jaws by the yielding shoe support.

10. In a device of the class described arranged to operate upon a lasted upper, means on each side for engaging the upper at the shank to draw the same tight, a cutting stop on said means, and a stop to locate the upper at a predetermined position relative to said cutting stop.

11. In a device of the class described a longitudinally movable support for a lasted and welted upper, a welt cutting stop on each side of said support, and a stop to locate said support at a predetermined position relative to said cutting stop.

12. In a device of the class described, a narrow finger arranged to extend under the butt portion of the welt of a welted shoe, said finger having a raised formation in

view of the operator when the shoe is in the machine to indicate the point at which the welt should be cut in butting it.

13. In a device of the class described, 5 oppositely acting narrow fingers arranged to extend under the butt portions of the welt of a welted shoe and having raised formations in view of the operator when the shoe is in the machine to facilitate the 10 butting of the welt at corresponding points at the two sides of the shoe.

14. In a device of the class described, a back stop for a shoe and a finger which are relatively adjustable lengthwise of the shoe, 15 said finger being arranged to extend under the welt of a welted shoe and having a formation constructed and arranged to guide the operator in the butting of the welt at a predetermined point with relation to the 20 back stop.

15. In a device of the class described, a finger having a portion formed to extend into the welt crease of a welted shoe and a portion of different formation to extend 25 under and lift the butt end of the welt from the shoe bottom and support it in position to be cut.

16. In a device of the class described, a finger having a portion formed to extend 30 into the welt crease and press against the inseam and a portion of different formation to support the butt end portion of the welt in position to be cut and having a raised face to coöperate with a blade in cutting 35 off the butt of the welt.

17. In a device of the class described, oppositely acting narrow fingers arranged to extend under the butt portions of the welt of a welted shoe to tighten the upper and 40 hold it while it is secured and the welt is butted and a back stop for the shoe adjustable relatively to said fingers to facilitate the securing and butting at predetermined 45 points with relation to the length of the shoe.

18. In a device of the class described, the finger 14 having the bend 14¹, the pressing edge 14², and the raised welt end supporting face 15.

19. A machine for working the upper into lasted position adjacent to the ends of the heel stiffener of a shoe having an outturned sole attaching flange, comprising means 50 constructed and arranged to engage the shoe stock at opposite sides of the shoe to tighten the upper about the last adjacent to the end of the stiffener relatively to the upper at the ball of the shoe and hold the upper in tightened condition while it is operated 55 upon.

20. A machine for working an upper into lasted position adjacent to the ends of the heel stiffener of a shoe having an outturned

sole attaching flange, comprising means constructed and arranged to engage the shoe 65 stock for a limited distance adjacent to the ends of the stiffener, and mechanism for actuating said means to tighten the upper about the last at the engaged points relatively to the upper in the shank and to hold 70 the tightened upper under tension while it is fastened.

21. In a machine of the class described, the combination with the devices 14 movable transversely over the shoe bottom, of 75 the yielding shoe support arranged to permit the shoe to be introduced endwise between said devices, and the adjustable back stop to limit the introduction of the shoe.

22. A machine of the class described having devices for engaging the end portions only of the welt simultaneously at the two sides of a shoe, and means for actuating said devices to move the welt end relatively to the body portion of the welt for positioning the two welt ends in substantially the same relation to the two sides of the shoe and holding them in position to be operated upon.

23. A machine of the class described having devices for forcing the stock adjacent to the ends of the inseam of a welted shoe inwardly over the last, mechanism for actuating said devices, and means for pressing the shoe upwardly against said devices during 95 their actuation.

24. A machine of the class described having devices for forcing the stock adjacent to the ends of the inseam of a welted shoe inwardly over the last, mechanism for actuating said devices to tighten the upper and hold it while it is being fastened, and means for yieldingly pressing the shoe upwardly 100 against said devices whereby they are caused to hold the tightened stock snugly against 105 the last bottom.

25. A machine of the class described, having, in combination, pressers having short acting edges arranged to engage the welt crease at opposite sides of a shoe at and 110 adjacent the ends of the inseam, and means for actuating said pressers substantially horizontally to tighten the shoe stock at the engaged points relatively to the upper in the shank, and means for yieldingly pressing the last upwardly during the operation 115 of said pressers whereby the shoe stock is compressed between the pressers and the last bottom.

In testimony whereof, I affix my signature in presence of two witnesses.

CARL S. NORDEN.
